his attorney

UNITED STATES PATENT OFFICE.

RICHARD SCHRAMM, OF CINCINNATI, OHIO, ASSIGNOR TO THE NATIONAL MARKING MACHINE CO., OF CINCINNATI, OHIO, A CORPORATION OF OHIO.

SAFETY-PIN.

1,331,943.

Specification of Letters Patent. Patented Feb. 24, 1920.

Application filed January 18, 1919. Serial No. 271,907.

To all whom it may concern:

Be it known that I, RICHARD SCHRAMM, a citizen of the United States, residing at Cincinnati, in the county of Hamilton and State of Ohio, have invented certain new and useful Improvements in Safety-Pins, of which the following is a specification.

My present invention pertains to safety pins such as are designed particularly for use in the marking of laundry.

A material objection to the use of safety pins for laundry-marking purposes has developed from the liability of safety pins extant to catch in the cylinder perforations of washing machines and drying tumblers now generally employed, and which perforations in drying tumblers vary from one fourth of an inch to five sixteenths of an inch in diameter, in metallic cylinders of washing machines are fifteen-thirty seconds of an inch in diameter, and in wooden cylinders of washing machines are thirteen sixteenths of an inch in diameter. In the metallic cylinders the perforations are spaced one and one-fourth inches apart circumferentially of the cylinders, and the direction of the length of the cylinders the perforations are one and one eighth inches apart. The perforations of the wooden cylinders are one and one half inches apart circumferentially and two inches apart longitudinally.

Therefore one object of my invention is the provision of a safety marking pin which by reason of its form and construction is not liable to catch into any one of the perforations alluded to, and hence is adapted to contribute to the continuity of operation of washing machines and drying tumblers, and, at the same time, avert injury to clothes. Moreover the said capacity of function of my novel pin is not likely to be affected by any water-wear that may take place in connection with the perforations of wooden cylinders.

Another object of the invention is the provision of a safety pin made up of certain elements which are so assembled and connected of themselves that the pin is susceptible of economical production without the employment of skilled labor, and when produced is well adapted to meet the condition set forth and generally withstand the usage to which safety pins are ordinarily subjected.

To the attainment of the foregoing the

invention consists in the safety pin as hereinafter described and definitely claimed.

In the accompanying drawings, hereby made a part hereof:

Figure 1 is a front elevation of my novel safety pin with the tongue in open position.

Fig. 2 is a rear elevation of the same with the tongue in closed position.

Fig. 3 is an elevation of the pin frame.

Fig. 4 is an inner elevation and

Fig. 5 a longitudinal-central section of one head of the pin as the same appears precedent to application to the frame.

Figs. 6 and 7 are similar views of the other head.

Figs. 8 and 9 are similar views of the keeper-member carried by the last-named head.

Similar numerals of reference designate corresponding parts in all the views of the drawings.

The frame 1 of the pin is formed of one piece of spring steel wire or other material possessed of the requisite strength and resiliency. It comprises a body bar 2 having a curvilinear terminal 3 at one end thereof, a loop 4 at the opposite end of the body bar, and a tongue 5 into which the loop 4 merges.

With the loop 4 of frame 1 I combine the head 6, Figs. 1, 2, 4 and 5. The said head 6 is of brass or other suitable sheet metal and is of elliptical form in outline for important reasons hereinafter set forth. On the head 6 is a marginal flange 7, and through the said flange the head is strongly connected of itself to the frame loop 4, the flange being bent about the wire of the loop as appears in Fig. 2.

The second head 8 of the pin is formed of brass or other sheet-metal and is elliptical in outline, with a marginal flange 9, between ends of which an opening 10 is afforded. Combined directly with the head 8 is a keeper-member made up of an elliptical plate 11 held in and to the head 8 by the bent flange 9 thereof, and a keeper 12 provided by forming the plate 11 with an offset portion, best shown in Figs. 8 and 9, that is disposed in the flange opening 10, and against the ends of the flange 9, and is slotted longitudinally of the pin, as indicated by 13, the mouth of the slot being preferably contracted as shown. The terminal 3 of the frame 1 is snugly disposed and held in the bight of the

keeper 12, and the body bar 2 of said frame rests in the keeper 12 and adjacent to one end of the flange 9. This manifestly contributes to the strength and stiffness of the 5 pin. The tongue 5 is adapted to be sprung into and out of the keeper 12 and to and from a position against the opposite end of the flange 9, and consequently when the tongue 5 is in closed position it will also 10 contribute to the stiffness and strength of the pin.

It will be understood from the foregoing that one part of my invention resides in the construction and relative arrangement of the 15 elements whereby a stiff, strong and durable safety pin is formed or produced, and another and highly important part of the invention consists in a safety pin having spaced heads, of elliptical form in outline, 20 and which by reason of their form and relative arrangement are not liable to be caught in the perforations of washing machines and drying tumblers hereinbefore referred to.

As appears in Fig. 1 the heads 6 and 8 are 25 adapted to be provided on their front sides with marking numerals which are preferably arranged to read in the direction of the length of the heads.

Having described my invention, what I 30 claim and desire to secure by Letters Patent, is:

1. A laundry marking pin having a body, and flat heads, of elliptical form in outline, at the ends of the body and spaced apart; 35 the said heads being arranged edgewise in the same plane as the body and extended transversely in opposite directions beyond the sides of the body and in the same plane as said sides, with their greatest lengths at 40 angles to the length of the body.

2. In a laundry marking pin, the combination of a body bar having a loop at one end and a curvilinear terminal at its opposite end and also having a pin at the opposite 45 site end of the loop; said body bar, loop, terminal and pin all lying in the same plane, a sheet-metal head arranged alongside said loop and having a marginal flange bent

around the loop, a second sheet-metal head arranged alongside the curvilinear terminal 50 portion of the body bar in the same edge-wise plane as the first-named head and having a marginal flange and an opening between the ends of said flange, and a flat keeper member resting alongside the second-named head within and held by the marginal flange thereof and having an offset and slotted keeper portion between which and the second-named head the terminal portion of the body bar is received and held; 60 said offset and slotted portion being snugly interposed between the ends of the head flange and the pin of the body bar being movable inwardly and outwardly through the slot of said portion. 65

3. A laundry marking pin comprising a body and flat heads at the ends of the body and spaced apart and extending laterally, in the direction of the greatest width of the body.

4. A laundry marking pin comprising a body including a bar and a tongue in parallelism with and spaced from said bar, a flat head at one end of the body and fixed to said bar and tongue and extending laterally and in the direction of the greatest width of the body beyond the bar and tongue thereof, and a flat head at the opposite end of the body and spaced from the first-named head and fixed to the bar and 80 tongue and extending laterally and in the direction of the greatest width of the body beyond the bar and tongue thereof.

5. A safety marking pin that will not be 85 liable to catch into perforations of laundry machinery; the said pin having a body and flat heads at both ends of the body and spaced apart and extending laterally beyond both sides of the body.

In testimony whereof I affix my signature in presence of two witnesses.

RICHARD SCHRAMM.
